UNITED STATES PATENT OFFICE.

FRANK HOWARD LYND, OF MORRISTOWN, NEW JERSEY.

DESIGN FOR A CHEST.

Application filed May 22, 1925. Serial No. 13,534. Term of patent 14 years.

To all whom it may concern:

Be it known that I, FRANK H. LYND, a citizen of the United States of America, and a resident of Morristown, in the county of Morris and State of New Jersey, United States of America, have invented a new, original, and ornamental Design for a Chest, of which the following is a specification, reference being had to the accompanying drawing, forming part thereof.

Figure 1 is a front elevation of a chest embodying my design;

Figure 2 is a side elevation of a chest embodying the design;

Figure 3 is a plan view on a reduced scale.

I claim:

The ornamental design for a chest, as shown.

FRANK HOWARD LYND.
